UNITED STATES PATENT OFFICE.

MAX KRONAUER, OF PATERSON, NEW JERSEY.

LOCK-BAR PIPE.

No. 822,004.

Specification of Letters Patent.

Patented May 29, 1906.

Application filed June 17, 1905. Serial No. 265,653.

To all whom it may concern:

Be it known that I, MAX KRONAUER, a citizen of the Republic of Switzerland, residing in Paterson, county of Passaic, and State of New Jersey, have invented certain new and useful Improvements in Lock-Bar Pipes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that type of what are known as "lock-bar" pipes which is illustrated in my United States Letters Patent No. 773,945.

The present invention has for its object to perfect as far as possible that form of pipe in respect mainly to its ability to resist the tendency of internal pressure to disestablish or disrupt the joint produced. This is accomplished by making the extreme edge portion of the part of each plate which is embedded in the lock-bar stand bent off relatively to the remainder of the said embedded portion, so that the cross-section reveals an angle or bend in the said embedded portion. Preferably, and as herein shown, such bend is an outward one, so that the result is that with regard to the embedded portions of the two plates they stand farther apart at their extremities than where they enter the bar. The stability and strength of this construction, especially in the preferred form, wherein the tendency on the part of very high internal pressure to open the bar and cause the plate edges to slip out is at once resisted by the, as it were, hook-shaped form of the plates, will be at once apparent.

My improvement is illustrated in the accompanying drawings in three figures.

Figure 1 is a perspective view of a length of the improved pipe; Fig. 2, an enlarged cross-sectional view of the parts assembled before closing, and Fig. 3 a similar view of the part after closing.

In said drawings, *a* designates the plates, the same having their longitudinal edges bent off, preferably at right angles to the plane of the contiguous portions *b* of the plates, so as to form longitudinal flanges *c*, which after the plates have been assembled

in tubular disposition stand parallel or substantially parallel to each other, projecting, preferably, outwardly.

d is the lock-bar. This is formed with longitudinal grooves *e*, arranged in the side thereof which stands next adjacent to the plates in the final assemblage of the parts, and thus producing three longitudinal fins or jaws *f g h*. When the bar issues from its forming process, the base of the fin or jaw *g* is wider, as at *i*, than its extremity.

The plates being formed with the flanges *c*, as above described, and then assembled in the form of a tubular body, the bars are applied, the flanges *c* being inserted into the grooves *e* as far as the depths of the latter will permit. The bar is now compressed or squeezed, which action, on account of the form of the fin or jaw *g*, makes the parts have ultimately the form shown in Fig. 3, where each flange *c* has a kink or bend *j*, and the metal of the bar on both sides of such flange follows in form substantially the form of said flange.

It will be understood that I do not wish to be limited either to the specific form of the invention herein described and shown by way of explanation, nor to the manner in which the final result is attained.

What I claim is—

1. The combination of two sheet-metal bodies having their edge portions lying in substantially the same plane and projecting toward each other and a lock-bar joining and securing together said edge portions, the extremities of said edge portions being bent up out of said plane to form flanges and said lock-bar having longitudinal parallel grooves formed in the side thereof next adjacent said edge portions and receiving said flanges, each edge portion or flange having, within the lock-bar, a longitudinal bend or kink, and said lock-bar being interiorly shaped to substantially conform with said flanges, substantially as described.

2. The combination of two sheet-metal bodies having their edge portions lying in substantially the same plane and projecting toward each other and a lock-bar joining and securing together said edge portions, the extremities of said edge portions being bent up together out of said plane to form flanges and said lock-bar having longitudinal parallel grooves formed in the side thereof next said

edge portions and receiving said flanges, the portions of said flanges within the lock-bar having their free edges bent away from each other, and said lock-bar being interiorly shaped to substantially conform with said flanges, substantially as described.

5 In testimony that I claim the foregoing I

have hereunto set my hand this 13th day of June, 1905.

MAX KRONAUER.
